UNITED STATES PATENT OFFICE.

JOSEPH H. DIXON, OF WELLINGTON, OHIO.

DESIGN FOR A JUVENILE VEHICLE.

55,417.

Specification for Design.

Patented June 8, 1920.

Application filed December 24, 1919. Serial No. 347,236. Term of patent 3½ years.

To all whom it may concern:

Be it known that I, JOSEPH H. DIXON, a citizen of the United States, and a resident of Wellington, county of Lorain, and State of Ohio, have invented a new, original, and ornamental Design for a Juvenile Vehicle, of which the following is a specification, reference being had to the accompanying drawing, forming part thereof.

In said annexed drawing:—

The single figure there appearing is a perspective view of my new design.

I claim:—

The ornamental design for a juvenile vehicle, as shown.

Signed by me this 19 day of December, 1919.

JOSEPH H. DIXON.
